CLAIM

I claim the ornamental design for a utensil rest with lid holder, as shown and described.

DESCRIPTION

FIG. 1 is a top perspective view of a utensil rest with lid holder in accordance with the design;

FIG. 2 is a bottom perspective view of a utensil rest with lid holder;

FIG. 3 is a top plane view of a utensil rest with lid holder;

FIG. 4 is a side view of a utensil rest with lid holder;

FIG. 5 is a front side view of a utensil rest with lid holder;

FIG. 6 is a back side view of a utensil rest with lid holder;

FIG. 7 is a top perspective view of a utensil rest with lid holder in environments of use; and,

FIG. 8 is a side perspective view of a utensil rest with lid holder in environments of use.

The broken lines in FIGS. 7 and 8 illustrate the lid and utensils, which are environmental features and represent unclaimed subject matter and form no part of the claimed design.
